UNITED STATES PATENT OFFICE.

HENRY P. J. EARNSHAW, OF BOSTON, MASSACHUSETTS, ASSIGNOR TO EARNSHAW MANUFACTURING COMPANY, INCORPORATED, OF HARTFORD, CONNECTICUT, A CORPORATION OF CONNECTICUT.

COMPRESSED-AIR POWER PLANT.

1,292,731.

Specification of Letters Patent. Patented Jan. 28, 1919.

Application filed June 5, 1916. Serial No. 101,708.

To all whom it may concern:

Be it known that I, HENRY P. J. EARNSHAW, a citizen of the United States, residing at Boston, in the county of Suffolk and 5 State of Massachusetts, have invented certain new and useful Improvements in Compressed-Air Power Plants, of which the following is a specification.

This invention relates to what I shall for 10 convenience term a "compressed air power plant", the compressed air from the storage tank constituting a part of the apparatus, being usable for any desired purpose, but generally for effecting the action of a suitable tool. In machines of this nature, the air under compression is conducted from a compressor to a storage tank. When the compressed air enters the tank its temperature is quite high. From causes familiar 15 to those skilled in the art, the air as it passes along the tank is reduced in temperature, the reduction continuing as the air travels through the discharge duct or pipe of the storage tank and being so low that at certain 20 seasons it freezes the oil of an implement which the compressed air from the discharge duct operates. Various clumsy expedients have been adopted to overcome this difficulty, the one generally in vogue being the building 25 of a fire to heat the air in the discharge duct or pipe. Besides the natural disadvantages following this procedure there is the added danger of conflagrations. To prevent the compressed air at or in adjacency to the 30 tool being operated from freezing the oil or the water, I provide means preferably in constant relation with the said discharge duct by which the air can be heated before it reaches the tool to such an extent to prevent 35 this freezing. This particular result can be obtained in any desirable manner, for example by a heater governed by the motor for the air compressor. When said air compressor is operated by a steam engine as is the 40 case in the present instance, the exhaust steam can be utilized for heating the air in said discharge duct or pipe to the requisite extent, or high pressure or boiler steam can be thus utilized.

50 In the drawings accompanying and forming part of the present specification I have shown two of the several convenient forms of embodiment of the invention which I will set forth fully in the following description.

I do not limit myself to this particular disclosure; I may depart therefrom in several particulars within the scope of the invention defined by the claim following said description.

Referring to said drawings:

Figure 1 is a top plan view of an apparatus involving my invention.

Fig. 2 is a side elevation of said apparatus.

Fig. 3 is a top plan view of the reheater showing a different arrangement of piping, 65 the pipes being sectioned on the line 3—3 of Fig. 4, looking in the direction of the arrow.

Fig. 4 is a vertical sectional view on the line 4—4 of Fig. 3, looking in the direction 70 of the arrow.

Fig. 5 is an end elevation of the reheater as seen from the left in Figs. 3 and 4, the pipe connections being omitted.

Fig. 6 is a transverse section on the line 6—6 of Fig. 3, looking in the direction of 75 the arrow, the pipe connections being omitted.

Like characters refer to like parts throughout the several views which are on different scales.

I have alluded to the fact that I show two 80 forms of the invention. The reheater in both forms is the same, and in describing this it follows that similar characters will be used to denote corresponding parts. The principal difference between the showing of 85 Figs. 1 and 2 and that made by the remaining figures is in regard to the pipe connections as will hereinafter appear. Figs. 1 and 2 illustrate a reheater which is shown in detail in Figs. 3 to 6 inclusive.

90 Preferably, although not necessarily, the various parts of the apparatus are supported by a wheeled vehicle such as that denoted in a general way by 2. The platform or deck of the vehicle sustains a storage tank as 3 which can be supplied with compressed air 95 by a compressor as 4, the pipe 5 presenting a convenient means for conducting the compressed air from the compressor to the tank. The compressor may be operated by any 100 suitable motor, for instance the compound steam engine 6 adapted to be supplied with the necessary steam in any desirable manner, for instance by the pipe 7, leading from the steam space or dome of the boiler 8 represented as carried by the rear of the vehicle. It should be noted that while a steam engine as shown is the motor for effecting 105

the action of a compressor as 4, this may not in all cases be necessary. When, however, a steam engine is utilized for this purpose, the exhaust steam therefrom can be used to 5 heat the air, or steam from the boiler can be utilized for this purpose. Boiler steam is, of course under high pressure while the exhaust steam is at a lower pressure, and it follows that when a boiler and steam engine 10 are part of the equipment, either high or low pressure steam may be provided for heating the air.

Between the boiler 8 and the storage tank 3 there is disposed a water tank 9 connected 15 in some suitable way with the water space of the boiler and which constitutes a convenient support for a reheater such as that denoted in a general way by 10 and shown in both Figs. 1 and 2. This reheater is the 20 same as that illustrated in detail in Figs. 3 to 6, as I have already observed, so that it is obvious that if the reheater shown in the last mentioned views be set forth in detail, this applies to the reheater 10 shown 25 in Figs. 1 and 2. The reheater 10 comprises in its construction a casing as 11, having between its ends flanges or feet as 12 adapted to be connected in some convenient rigid manner with the water tank 9. One end of 30 the elongated casing or housing 11 is permanently closed, the other end being provided with a removable cap 13 adapted to be held in place normally by suitable means as the bolts 14. As illustrated the casing 11 35 receives a pipe 15 of return bend or U-form, the branches of the pipe extending through and closely fitting holes or perforations in the cap or plate 13, the bent portion of the pipe or heating member 15 being in proximity to the closed end of the housing or casing 11. As represented there is a pipe connection (Figs. 1 and 2) 16 leading from the air storage tank 3, this being connected to 40 what is shown as the upper branch of the heater 15, the air leaving the lower branch of said heater. In Fig. 4 the arrows 17 and 18 show the direction of flow of the air, the air after leaving the heater 15 being conducted by suitable means to a pneumatic tool 45 and being heated while in the heater to such an extent that the air cannot freeze any liquid that may be in the tool.

Referring now to Figs. 1 and 2, the numeral 19 denotes a pipe or duct constituting 50 suitable exhaust carrying means for the engine 6. From the pipe between the ends thereof, the branch pipe 20 extends, there being a valve 21 at the junction of the main and branch pipes. This pipe 20 is connected 55 in a steam-tight manner with the casing 11 of the reheater. There is connected with said casing 11 also in a steam-tight manner the branch pipe 22 which has a connection with the main pipe 19 back of the point of 60 connection therewith of the branch pipe 20,

there being a valve 23 where the pipe 22 is united with the pipe 19. It will be noticed that the pipes 20 and 22 are connected with the casing 11 at longitudinally spaced points, the pipe 20 being nearer the capped 70 end of the casing than the pipe 22. The pipe 19 at its rear is provided with upwardly and downwardly extending branches 24 and 25, the branch 24 opening into the stack 26 of the boiler, while the branch 25 opens to atmosphere. At its rear end the pipe 19 is provided with a valve 27 through which the exhaust can be directed at will into either the branches 24 and 25. It will be clear that if the engine 6 be in operation and that if 80 both valves 21 and 23 be open, exhaust steam from the engine will pass from the pipe 19 into the branch 20 and from the latter into the casing 11 circulating along the latter and leaving the same by the branch 22. From 85 this the exhaust passes again into the pipe 19 and leaving the latter follows one of the branches 24 and 25, depending upon the position of the valve 27. If the exhaust steam enters the branch 24, it is afterward 90 exhausted into the stack 26 and then to the atmosphere, whereas if it enters the branch 25, it goes directly to atmosphere. The exhaust steam entering the casing 11 effectually heats the air in the pipe 15 under ordinary conditions. There may be cases, however, such as in extremely cold weather where high pressure steam is necessary for effecting the desired heating of the air in the heater. For this purpose I have shown 100 the pipe 28 extending from the water column connection 29 of the boiler to the permanently closed end of the casing 11, this pipe being furnished with a valve 30 to admit boiler pressure steam as desired. Leading 105 from the casing to the water space of the boiler is the pipe 31 equipped with a valve 32 which can be opened to conduct the condensate into said casing to the water space 110 of the boiler.

Referring now to Figs. 3 to 6 inclusive, it will be understood that the pipes 28 and 31 and their adjuncts are shown in Fig. 3. Rising from the casing 11 near opposite ends thereof are the pipes 33 and 34 connected by the pipe 35, the pipe 36 connected with the pipe 33 between the casing 11 and the pipe 35 being provided to conduct exhaust steam from the engine 6. At the junction of the pipe 36 with the pipe 33 is a valve 37 120 while in the pipe 34 is a valve 38. When it is desired to utilize the exhaust steam to heat the compressed air in the pipe 15, the valves 37 and 38 are positioned as shown in Fig. 4, the course of the exhaust steam 125 being indicated by the arrows. With the parts in this relation the steam passing from the pipe 36 enters the pipe 33 below the valve 37, then enters and travels along the casing 11, passing therefrom into the 130

- pipe 34, pipe 35 and then into the upper part of the pipe 33 from which the said steam may be discharged into the atmosphere or otherwise disposed of. In said Fig. 3 arrows also show the course of the air into, from and then along the pipe or heater 15. The valve 37 can be moved to the dotted line position in Fig. 4 to divert the exhaust away from the casing 11 and into the upper part of the pipe 33. In this latter case the valve 38 will be closed as also shown by dotted lines in said Fig. 4. In the pipe 35 is a check valve 39 which opens toward the left in Fig. 4. In this view it is shown as occupying its open position by full lines and its closed position by dotted lines, being opened by the power of the exhaust steam after the latter has served its function of heating the air in the pipe 15. If the valve 37 be moved to the dotted line position in said Fig. 4 and the valve 38 also closed, the steam will move the check valve 39 to closed position and thus prevent the steam from entering the casing 11. It may be in the latter case that the valve 30 will be opened so as to supply boiler pressure steam into the casing 11, and in this particular condition exhaust steam may not be utilized. As a matter of fact there may be cases such as in excessively warm weather or even moderately warm or in indoor work that it may not be necessary to have recourse to the steam.
- When the engine 6 is in operation, it will be clear that it operates the compressor 4, and the latter in turn supplies compressed air to the tank 3 which passing therefrom by way of the pipe 16 enters the upper branch of the return bend pipe 15 and leaves the lower branch thereof as already noted, being conducted by suitable piping or other-
- wise to a proper tool or conveniently utilized for the intended purpose. If necessary the air in the pipe 15 can be heated by steam in either of the ways already set forth. As will be obvious I do not restrict myself to the heating of the air in this particular manner, for the purpose can be accomplished with equal advantage in other fashions.
- It will be apparent that the return bend pipe 15 which I have described as a heater is actually such, or at least a part of a re-heater. In the present case it constitutes also a part of the discharge piping for the compressed air of the storage tank.
- What I claim is:
- In an apparatus of the class described, the combination of a compressed air storage tank and a discharge pipe therefor, said discharge pipe having a return bend, a casing receiving said return bend, a steam boiler, an engine operated by the steam from the boiler, an air compressor for supplying compressed air to said tank and operated by said steam engine, a pipe extending from said casing at one end thereof and having a valve, a second pipe extending from the casing near the opposite end thereof and also having a valve, a connecting pipe uniting the other pipes at a point outward beyond the valves therein and having a check valve, and a pipe for conducting exhaust steam from the engine to the first mentioned pipe at the point where the valve is located therein.
- In testimony whereof I affix my signature in the presence of two witnesses.

HENRY P. J. EARNSHAW.
